(57) CLAIM

I claim, the ornamental design for a jewelry chain, as shown and described.

DESCRIPTION

FIG. 1 is a front elevation view of a jewelry chain, showing my new design, the opposite rear side being a mirror image thereof;

FIG. 2 is a front perspective view thereof with the jewelry chain in an alternate position;

FIG. 3 is an enlarged partial perspective view thereof showing a link of the jewelry chain;

FIG. 4 is a side elevation view of the jewelry chain of FIG. 1; and,

FIG. 5 is an enlarged partial perspective view thereof.
